UNITED STATES PATENT OFFICE

2,328,254

CHAIR BED

Joseph D. Bell, San Francisco, Calif.

Application May 16, 1940, Serial No. 335,593

5 Claims. (CL 5—48)

The present invention relates to improvements in chair beds, and this application is a continuation in part of my copending application, Serial Number 309,855, filed December 18, 1939.

The general object of the invention is to provide improvements in a chair bed constructed in such a manner that it may be conveniently operated by an occupant between chair and bed positions by the mere shifting of weight of the body of the occupant.

More particularly it is proposed in the present invention, to arrange the chair in such a manner that it may be changed from a chair into a bed without causing the rear edge to project rearwardly very far beyond its original rear plane. This feature allows a chair of the character described to be placed with its top rear edge relatively close to the wall of a room and to be changed into a bed without the necessity of moving the chair bed as a whole.

It is further proposed in the present application to provide a chair bed comprising a main supporting frame and a movable frame structure including rigid back and seat sections hinged together and means for supporting the frame structure on the main frame with freedom of floating movement between chair and bed positions.

Another object of my invention is to provide a peculiar link mechanism as a support for the movable frame structure, the said mechanism allowing the back section to rock on an intermediate support when the upper end of the back is pressed downward and, at the same time, exerting a forward pull on the back section, whereby the entire movable frame is pulled forward toward bed position.

A further object of the invention is to provide an improved supporting means for the seat causing the latter to advance and rise to a position of alignment with the back section as the latter is tilted and lowered into horizontal position.

And finally, it is proposed to provide yielding locking means for the seat supporting means arranged in such a manner, that in combination with the back supporting means, it acts to hold the hinge between the back and the seat against collapse.

Further objects and advantages of my invention will appear as the specification proceeds, and the novel features of my chair bed will be fully set forth in the claims hereto appended.

The preferred forms of my invention are illustrated in the accompanying drawing, in which:

Figure 1 shows a longitudinal section through one form of bed chair;

Figure 2, a similar section through a modified form of chair bed, in chair position;

Figure 3, a longitudinal section similar to that of Figure 2, and showing the chair bed in bed position;

Figure 4, a fragmentary perspective view of the main operating portion in a further modified form;

Figure 5, a fragmentary perspective view, similar to that of Figure 4, but showing the elements in bed position; and

Figure 6, a view similar to that of Figure 3, but showing the link mechanism as a mere mechanical movement.

While I have shown only the preferred forms of my invention, I wish to have it understood that various changes or modifications may be made within the scope of the claims hereto attached without departing from the spirit of the invention.

Referring to the drawing in detail, Figure 1 shows a main frame 1 comprising side members 2 adapted to serve as arm rests for an occupant of a chair and end members 3 and 4, one in the rear of the frame and the other in the front thereof.

The front member is shown as being slightly higher than the rear member, and the frame is preferably supported on short legs 5.

The movable frame structure 6 comprises a back frame 7 and a seat frame 8, the two frames being hinged together, as at 9, for swinging movement between angular and aligned positions. Suitable upholstery 10 covers the entire movable frame structure from end to end and moves with the same, the upholstery being constructed to furnish a perfectly smooth surface in bed position and to throw an inwardly turned fold, as at 11 in chair position.

The structure of the upholstery is substantially the same as that disclosed in my co-pending application, Serial Number 309,855, above referred to.

An extension 12 is normally housed underneath the seat and is hinged to the front edge thereof, as at 13, and is provided with folding legs 14 adapted to be accommodated between the extension and the bottom of the seat section in chair position.

It is apparent that upon lifting the front edge of the seat, the extension may be swung outward into alignment with the seat, and the legs may be swung outward into supporting relation with

the front edge of the extension, substantially in the manner shown in slightly modified form in Figure 3.

For supporting the movable frame structure, I provide a pair of links 15 pivoted to the lower portion of the main frame near the rear wall thereof, as at 16, and to the back section along a horizontal line intermediate its height, as shown at 17. When in chair position, as shown in Figure 1, the link 15 projects about half way above the rear wall 3, and leans against the latter, and the back section is free to tilt on the pivot 17, while the link itself is free to swing forward on its pivot 16. The weight of the seat, the front edge of which rests on the front wall 4, through the extension 12, normally prevents such forward movement.

To insure forward movement, upon the tilting back of the upper part of the back section, I provide a link mechanism including links 18, 19 and 20. The link 18 has its lower end pivoted to the main frame near the bottom and the front thereof, as shown at 21, and the upper end of the link is connected, through the link 20, to the lower end of the back section near the hinge 9.

The link 19 interconnects intermediate points of links 15 and 18, as at 22 and 23. The link 18 is curved in its upper end so as to allow the same to be swung forward sufficiently far for the purposes of the present invention before striking the front wall 4, on which it comes to rest at the end of the forward movement.

It will be noted from Figure 1, that in the position indicated, the link 19 forming a brace between the two links 15 and 18, prevents rearward movement of the latter, which, through the link 20, holds the lower portion of the back against backward movement.

When a person seated on the chair or standing beside the same bears down on the upper portion of the back, the latter rocks on the pivots 17, whereby the lower end of the back is swung forward. This forward movement is immediately communicated through the links 20 and 18 to the link 19, which in turn, pulls forward on the link 15, so as to cause the pivots 17 to move forward immediately in response to the rocking movement. The link 18 thus becomes a draw member for pulling the entire unit forward when the upper end of the back is tilted backward.

At the end of the forward movement, the link 18 comes to rest on the front wall 4, and the link 15 swings forward sufficiently far to cause the back section to come to rest on the rear wall 3 in horizontal position, substantially as shown in connection with a modified form in Figure 3.

In the form of Figure 1, the chair bed is shown as being positioned relatively close to a wall 24, and the link mechanism for this chair is arranged to allow the extending operation to be carried out without moving the chair.

The form shown in Figures 2 and 3 differs from that of Figure 1 insofar that it provides for a lower seat and requires a cushion to bring the seating surface to normal height in chair position. In this form, the front wall 4' is considerably lower than the rear wall 3, and the seat is supported by a shoe or bracket 26 having an extended inclined front face and a substantially flat bottom 28, which has a downwardly projecting ridge 29, preferably V-shaped in cross section.

The front wall 4' has a cleat 30 attached thereto, which forms a groove 31 with the front wall adapted to receive the ridge 29 and to hold the

shoe against movement in either direction. This hold is not positive, like a locking means, but will offer sufficient resistance under given conditions for the purposes of the invention. If a positive lock is desired, a stop 29' may be added in the back of the shoe to bear against the rear edge of the cleat 30 for preventing forward movement of the seat, as shown in Figures 2 and 3.

10 In this form, the link arrangement corresponds substantially to that of Figure 1, except that the front link, identified as 18', does not have the curve and is not called upon to do any supporting in its forward position, since the shoe 26 takes care of this feature, and that the link 28' is attached to the back through a slot 17' to allow a certain amount of play.

15 In ordinary chair position, the links 15 of this form, may rest against the back 3 or lean forward slightly, the weight of the seat preventing forward movement of the lower end of the back section, and the links 18', 19' and 20' preventing rearward movement thereof. As the upper end of the back is tilted backward, the lower end moves forward and the links 18', 19' and 20' cooperate in dragging the pivot 17 forward until the back section comes to rest in a horizontal position with a rear portion resting on the back wall 3.

20 As the lower end of the back section moves forward, it pushes the seat section forward, causing the shoe 26 to ride on the front wall, whereby the seat is raised into a position of horizontal alignment with the back. When the seat reaches this position, the ridge 29 in the bottom of the shoe comes to rest in the groove 31, and is yieldingly held therein against movement in either direction. The extension 12 may be swung forward in the manner previously described.

25 It is interesting to note in connection with the bed position of Figure 3, that in this form the problem of holding the hinge against downward collapse is solved without the provision of a direct support at least as far as normal use is concerned. The links 18', 19' and 20' may be disregarded as supporting means, and the hinge itself is held solely by the link 15 cooperating with the back wall 3 on one hand, and the shoe cooperating with the front wall, on the other hand.

30 If a person lying on the bed should concentrate all his weight on the hinge, he would still be unable to cause the hinge to collapse, for the following reasons: In collapsing, the hinge would have to pass between the pivotal points 17 and 29, and one of these points would have to yield. The ridge 29 would not yield because the weight of the occupant would tend to intensify the engagement and point 17 would not yield because it would have to move upward against the weight of the occupant. This presupposes, of course, that an occupant, in concentrating his weight on the hinge, would exert pressure on an area on both sides of the hinge. If a weight were applied exclusively on the hinge, the pivot 17 might move upward and cause the bed to collapse.

35 The link 15 and the back wall 3 cooperate in preventing the hinge from moving upward, and since the engagement of the ridge 29 in the groove 31 prevents rearward movement of the bottom of the shoe, it is apparent that a person may sit on the extreme projecting end of the seat without causing the hinge to buckle upward.

40 To change from the position of Figure 3 to that of Figure 2, it is merely necessary to lift the projecting end of the back, which will raise the pivot

17 and lift the ridge 29 out of the groove 31 without any great effort.

The link construction shown in Figures 4 and 5 is slightly different. The link 20 of Figure 1 is omitted, and the link 18' is connected to the seat in a releasable manner. The upper end of the link has a pin 32 projecting therefrom, and the seat is formed with a bracket 33 having a downwardly opening slot 34 fitting over the pin 32. This construction allows the seat to be raised on its hinge, as shown in dotted lines in Figure 5, for the purpose of operating the extension.

When the seat is swung back, the slot automatically reengages over the pin 32. It will be noted that in all forms shown the operating mechanism is arranged in such a manner that the seat is always free for upward swinging movement to give access to the extension.

It should be understood that throughout the specification, where the term "link" has been used in the singular, this has been done for the sake of simplicity, and that, in reality the same link mechanism is used on both sides of the chair bed.

I claim:

1. In a chair bed, a main frame having a front supporting member, a seat having a shoe depending therefrom, the shoe having an inclined face slidable on the supporting member for raising the seat when it is advanced, and a notch in the supporting member and a V-shaped projection on the shoe engageable in the notch for opposing movement of the seat when it has reached a desired advanced position.

2. In a chair bed, a main frame, a back and a seat having a hinge connection between the same and means for supporting the back and seat on the frame in chair position, comprising two links, each pivoted to the main frame near the bottom thereof, one in the rear and the other forwardly thereof, and both rising from their pivots, the rear one substantially vertically and the front one with a slight rearward incline, a pivotal connection between the free end of the first link and the back intermediate its height, a third link connecting the free end of the second link and the back near the bottom thereof, and a fourth link connecting intermediate sections of the first two links, whereby the second link is swung forward

when the upper end of the back is swung rearward and through the fourth link pulls the first link forward.

3. In a tiltable back rest, a supporting base, a link having one end pivoted to the base, a rest connected intermediate its top and bottom to the other end of the link and tiltable thereon, means for normally holding the rest in upright position to serve as a back for a chair, a second link having one of its ends connected to said base, a third link connecting intermediate portions of the two links, and a connection between the free end of the second link and the lower end of the rest operable, as the upper end of the rest is tilted backward from its normal position, to bodily draw the latter forward in immediate response to the backward tilting movement.

4. In a chair bed, a main frame, a back, two links, each pivoted to the main frame near the bottom thereof, one in the rear and the other forwardly thereof, a pivotal connection between the free end of the first link and the back intermediate the latter's height, a third link connecting the free end of the second link and the back near the bottom thereof, and a fourth link connecting intermediate portions of the first two links, the back being operable for tilting rearward by manual pressure applied rearwardly at the top thereof, to draw forward the intermediate link and to be moved forward bodily by the said operation, a seat having hinged connection with the back and means for mounting the seat with freedom of movement in response to the movements of the back.

5. In a chair bed, a main frame, a rearwardly tiltable back, two members, each pivoted to the main frame near the bottom thereof, one in the rear and the other forwardly thereof, a pivotal connection between the free end of the first member and the back intermediate its height, a third member connecting the free end of the second member and the back near the bottom of the latter, and a fourth member connecting intermediate portions of the first two members, the back being operable by pressure rearwardly applied on its top, to draw forward the fourth member and by the said operation to be drawn forward bodily.

JOSEPH D. BELL.
